UNITED STATES PATENT OFFICE.

SEWARD P. COBB, OF SOUTH DANVERS, MASSACHUSETTS.

IMPROVED MACHINE FOR FINISHING LEATHER.

Specification forming part of Letters Patent No. 40,735, dated December 1, 1863.

To all whom it may concern:

Be it known that I, SEWARD P. COBB, a resident of South Danvers, in the county of Essex and State of Massachusetts, have invented an Improved Machine for Dicing, Polishing, or Finishing Leather; and I do hereby declare the same to be fully described in the following specification, and represented in the accompanying drawings, of which—

Figure 1 is a side elevation, Fig. 2 a front elevation, and Fig. 3 a vertical section, of such machine.

The nature of my invention consists as follows: First, in a peculiar mechanism for obtaining the compound movement of the vibrator or dicing-staff; also, in the combination and arrangement of a brush or cleansing mechanism with the dicer or finishing-tool and its staff or vibrator; also, in the combination and arrangement of an adjustable smoothing-tool with the dicer and its staff; also, in the combination and arrangement of a dicer-cleansing mechanism with the dicer, its staff, and curved bed.

In the drawings, A exhibits a table, from and above which a frame, B, extends, and serves to support the fulcrum *s* of a rocker-lever, C, which is arranged as shown in the drawings. The dicing-staff or vibrator D is jointed to one arm of the said rocker-lever, and at its lower end supports the slicker, dicer, or finishing-tool *a*, which is fastened to a tilting plate or frame, *b*, hinged to the lower end of the vibrator or dicing-staff D. A forked connecting-rod straddles the vibrator, and is jointed to it and to the crank-pin of a fly-wheel, E. Furthermore, there is jointed to the connecting-rod, within its fork and at a short distance from the dicer-staff, a pitman, *c*, which extends upward and at or near its upper end is jointed to the rocker-lever C, hereinbefore described, the arrangement of the said pitman with respect to the dicing-staff and rocker-lever being as shown in Figs. 1 and 3.

On revolving the fly-wheel in the direction of the arrow *y*, marked thereon, the dicer-staff will not only be vibrated with a pendulous motion, but while moving toward the fly-wheel the said dicing-staff will be moved or pressed downward toward the bed in manner to keep the dicing or finishing tool in contact with a piece of leather when on the bed. So, while moving away from the bed the dicing-staff

will be raised upward so as to elevate the dicer or polishing-tool entirely off and keep it out of contact with the leather.

In advance of the polisher or dicing-tool there is arranged a brush, H, held by a suitable supporting-frame, *d*, having one or more springs, *e*, so arranged and applied to it and the dicer-staff as to press the brush in a downward direction and upon the leather while such leather may be resting on the bed G. This brush moves with the dicer and its staff, and is for the purpose of removing from the surface of the leather, and in advance of the dicer, any dirt, grit, or any extraneous matter that may collect on the leather and be likely to cause injury to its surface from the action of the dicer. There is also placed to the rear of the dicer a smoothing-tool, I, it being carried by a clamp, *f*, attached to the dicer-staff. A spring, *g*, suitably applied to the smoothing-tool, serves to depress it, as occasion may require. The object of the smoothing tool is to remove from the surface of the leather, while the machine may be at work, more or less of the graining made by the dicing-tool, or, in other words, to tone down the graining as may be desirable. The said smoothing-tool may also be employed irrespective of the dicing-tool, and either one or both may be used, as occasion may require. A rod, *i*, jointed to the tilting plate *b* of the dicing-tool, extends upward along the dicer-staff, the said rod at its upper end being jointed to the shorter arm of a lever, *k*, whose fulcrum *l* is supported by the dicer-staff. This lever projects from the dicer-staff, and has projecting from its longer arm a pin or stud which goes between the prongs of a forked lever, *m*, formed and arranged as shown in the drawings. By laying hold of the longer arm of said forked lever and moving the same the dicer-tilting frame may be either raised or lowered, as circumstances may require.

At the front end of the curved bed G there is arranged a dicer cleaning tool or scraper, *o*, which is supported by a vibratory lever, *p*, to which vibrating movements may be imparted by means of a foot-lever, *q*, and a connection-rod, *r*, the same being arranged as shown in Figs. 1 and 3. By elevating the scraper previous to the expiration of any advance movement of the dicer, the said dicer, in the continuation of its movement, will be carried in contact with the scraper in such manner as to

be cleaned or scraped thereby. In this way the grease or dirt which may collect on the dicer or polishing tool may be removed therefrom.

I claim—

1. The peculiar mechanism for obtaining the compound movement of the dicing-staff D, the same, consisting of the fly-wheel E, the connecting-rod F, the rocker-lever C, and pitman e, arranged and so as to operate substantially as hereinbefore specified.

2. The combination and arrangement of the

brush H or leather-cleaning mechanism with the dicer a and its staff D.

3. The combination and arrangement of the adjustable smoothing-tool I with the dicer a and its staff.

4. The combination and arrangement of the scraper o or cleaning mechanism with the dicer a and its curved bed G.
